UNITED STATES PATENT OFFICE.

JOHN J. TOMEY, OF TRENTON, NEW JERSEY.

FLOOR-COVERING.

1,378,498.

Specification of Letters Patent. Patented May 17, 1921.

Application filed June 21, 1918. Serial No. 241,123.

To all whom it may concern:

Be it known that I, JOHN J. TOMEY, a citizen of the United States, residing in the city of Trenton, State of New Jersey, have 5 invented a certain new and useful Improvement in Floor-Coverings, of which the following is a specification.

My invention relates to floor coverings which may be described broadly as being 10 made of plastic material and which are impervious to water, and it has for one of its objects to provide a new covering comprising a bituminous material as a base. More particularly, my invention has for one of 15 its objects to provide a floor covering of the character indicated, comprising asphalt as a base.

A further object of my invention is to provide a floor covering of the character 20 indicated having reinforcing means to prevent the buckling and cracking of the covering after it has been laid upon a floor.

Other objects and advantages of my invention will be referred to and pointed out 25 in the detailed description thereof which follows or will be apparent from such description.

In order that my invention may be more readily understood and its practical and 30 commercial advantages more fully appreciated, reference may be had to the accompanying drawing in which I have illustrated certain forms of embodiment of the same and in which,—

35 Figure 1 is a perspective view of a portion of floor covering constructed in accordance with my invention;

Fig. 2 is a transverse, sectional view of 40 the same; and

Fig. 3 is a transverse, sectional view of 45 a modified construction of floor covering embodying my invention.

Referring to the drawing, 1 designates a substantially square portion of floor covering 50 constructed of bituminous materials combined with a filler in accordance with my invention. Although the portion of floor covering shown in Fig. 1 is in the form of a square, I desire it to be understood that my invention is not limited to the form of sheet illustrated. The sheets 55 may be constructed in long lengths and of relatively great width as in the case of the well known floor covering, linoleum.

The floor covering as constructed by me 60 and as embodying my invention, comprises

as a base, asphalt, although I do not wish my invention to be limited to that particular material, as it is obvious that an equivalent hydro-carbon or bituminous material 60 may be employed. In addition to the asphalt base, the floor covering includes a filler, which may comprise cork, wood flour, whiting, feldspar, Portland cement, lime and kauri gum. It will be understood, however, 65 that the ingredients constituting the filler may be varied, certain of them being omitted, and also other ingredients than those mentioned, if found to be suitable as fillers, may be employed.

In the construction of a floor covering embodying my invention, I employ the asphalt base material and a filler in the proportion of approximately forty to sixty. It will be understood, however, that this proportion may be varied if desired.

It is necessary only that the proper amount of filler be employed to render the asphalt easily workable and stiff and firm at the highest summer temperature or at the 80 highest room temperature to which the covering is liable to be subjected.

In order to control to a certain extent and in a practical way the contraction and expansion of the floor covering after it has 85 been laid and to prevent the buckling and cracking or fracturing or the same, I provide a reinforcing means consisting of a metallic structure. In the construction as illustrated, this structure consists of a wire 90 mesh or screen 2. Instead, however, of using a wire screen such as is shown, I may substitute therefor a sheet or sheets of expanded sheet metal, which expanded sheet metal construction is a well known article 95 of commerce, or any other metal sheet of reticular construction. This reinforcing sheet is embedded in the bottom surface of the asphaltic sheet. Such embodiment or embedding of the reinforcing metallic 100 structure in the bottom surface or bottom portion of the asphaltic sheet may be effected by forming the asphaltic sheets upon the same or by pressing the sheets after the same are formed upon the wire screen or 105 other metallic structure, such as expanded sheet metal. The reinforcing metallic structure, as will be observed, is so embedded in or pressed into the bottom surface of the asphaltic sheet that it does not project beyond the bottom surface of said sheet, 110 although its lower or bottom surface may be

partially or wholly visible. In other words, the lower side of the metallic reinforcing means may be described as being practically flush with the lower or bottom surface of the 5 asphaltic sheet.

It may be desirable in certain cases to provide the asphaltic floor covering with a top layer or covering of linoleum. If this should be so, such top layer or covering 10 may be provided as indicated at 3 in Fig. 3. In such case the asphalt sheet and the linoleum sheet are secured together merely by pressure, the said sheets, however, having been previously warmed sufficiently to 15 impart to their surfaces satisfactory adhesive qualities so that when pressed against each other they adhere tightly together. If

preferred a separate adhesive material may be employed to secure the sheets together.

When a linoleum sheet is employed as 20 shown in Fig. 3 it may comprise any ornamental design desired.

I claim:

A floor covering, consisting of a sheet of asphaltic material, a sheet of linoleum secured thereto and constituting the top of the covering and a reinforcing reticulated metallic sheet embedded in the bottom side of the first named sheet. 25

In testimony that I claim the foregoing 30 as my invention, I have hereunto signed my name this 18th day of June, A. D. 1918.

JOHN J. TOMEK.
